ABSTRACT

The present invention relates to a metal protective net, including: multiple steel wires arranged in parallel; multiple metal connecting sheets arranged in parallel, where the metal connecting sheets and the steel wires are arranged to intersect with each other at multiple intersections without being connected; insulating members which are provided between the steel wires and the metal connecting sheets and located at the intersections, and fixedly connected therewith; and connecting terminals, where both ends of each steel wire each are connected with one connecting terminal, and both ends of each metal connecting sheet each are connected with one connecting terminal; and a monitoring device electrically connected with the connecting terminals. The steel wires and the metal sheets, which form the metal protective net, are not electrically conductive with each other, forming many individual loops. If the metal net is broken, an alarm can be sent by the monitoring device.

METAL PROTECTIVE NET AND PROTECTION MONITORING SYSTEM**CROSS-REFERENCE TO RELATED APPLICATION**

The present application claims priority to a Chinese patent application No. CN201620336691.7, filed with the State Intellectual Property Office on Apr. 20, 2016, entitled "Metal Protective Net", which is incorporated herein by reference in its entirety.

TECHNICAL FIELD

The present invention relates to the technical field of monitoring and protection, and particularly to a metal protective net and a protection monitoring system.

BACKGROUND ART

In the prior art, boundary protection and boundary monitoring are two separate parts. Specifically, a common protective net is installed, followed by a monitoring device, which makes it unable to integrate protection with monitoring.

DISCLOSURE OF THE INVENTION

In view of such deficiencies in the prior art, an object of the present invention is to provide a metal protective net.

Another object of the present invention is to provide a protection monitoring system having the above metal protective net.

Embodiments of the present invention are realized through the following technical solutions.

A metal protective net, including:

a plurality of steel wires, where the plurality of steel wires are arranged in parallel;

a plurality of metal connecting sheets, where the plurality of metal connecting sheets are arranged in parallel, and the metal connecting sheets and the steel wires are arranged to intersect with each other at a plurality of intersections without being connected;

insulating members, where the insulating members are provided between the steel wires and the metal connecting sheets and located at the intersections, and fixedly connected with the steel wires and the metal connecting sheets;

connecting terminals, where both ends of each of the steel wires each are connected with one connecting terminal, and both ends of each of the metal connecting sheets are connected with two different connecting terminals; and

a monitoring device, where the connecting terminals are electrically connected with the monitoring device.

With the provision of the insulating members and the monitoring device, the steel wires and the metal sheets, which form the metal protective net, may be insulated from each other, i.e., not electrically conductive with each other, thereby forming many individual independent loops. If the metal net is damaged or broken, an alarm of the breakage information may be sent by the monitoring device (which may be an on-site audible and visual alarm, or may be uploaded in a wired or wireless way to an upper device for alarming). In the present invention, a multi-loop information transmitting channel is formed, and the integration of protection and monitoring is achieved.

2

Furthermore, the metal connecting sheet includes:

a first metal sheet, where the first metal sheet is arranged on one side of the plurality of steel wires, forming a plurality of intersections;

5 a second metal sheet, where the second metal sheet is arranged on the other side of the plurality of steel wires and located at the plurality of intersections;

the steel wire is fixed, at each of the plurality of intersections, with one of the insulating members by bonding or riveting, and the first metal sheet and the second metal sheet are both fixedly connected with the insulating member.

By providing two layers of metal sheets and locating the two layers of metal sheets at both sides of the steel wires respectively, the metal sheets may hold the insulating member tightly, forming tight intersections in the metal net.

Furthermore, both the first metal sheet and the second metal sheet are fixedly connected with the insulating member by mold stamping.

20 Furthermore, the insulating member is of a cylindrical shape, and the insulating member is sleeved outside the steel wire, and fixed with the steel wire. The metal sheets are bonded or riveted on an outer wall the insulating member.

Furthermore, the insulating member is of a cylindrical shape, and the insulating member is sleeved outside the steel wire, and fixed with the steel wire by bonding or riveting.

By setting the insulating member to be in a cylindrical shape and sleeved outside the steel wire, the steel wire can be effectively isolated from the metal sheet.

25 Furthermore, the first metal sheet and the second metal sheet are provided thereon with burrs, with the burrs located between adjacent two of the steel wires.

30 By providing burrs on the metal sheets, the protective effect can be further enhanced in the aspect of hardware.

Furthermore, every adjacent two of the steel wires are connected end to end successively via a conducting wire, so as to form a first conductor. Every adjacent two of the metal connecting sheets are connected end to end successively via a conducting wire, so as to form a second conductor. One 35 end of the first conductor and one end of the second conductor are both connected, via a conducting wire, with one connecting terminal, and the other end of the first conductor and the other end of the second conductor are both connected, via a conducting wire, with one connecting terminal.

40 Furthermore, the steel wire is a steel thread or iron thread having a cross-sectional diameter of 4 mm to 5 mm.

A metal protective net, including:

45 a plurality of first conductors, where the plurality of first conductors are arranged side by side, and connected end to end successively, forming a continuous conductive path;

50 a plurality of second conductors, where the plurality of second conductors are arranged side by side, and connected end to end successively, forming a continuous conductive path; and

55 insulators;

where the first conductors and the second conductors are arranged to intersect with each other, and the first conductors and the second conductors are connected at intersections to 60 form a net; the insulators are provided at the intersections between the first conductors and the second conductors, and the insulators are configured to make the first conductors and the second conductors non-conductive with each other.

Furthermore, the plurality of first conductors are formed by bending one metal conducting wire at several points.

65 Furthermore, the metal conducting wire is wrapped by an insulating layer, and a part of the insulating layer, which is

located at the intersection between the first conductor and the second conductor, forms the insulator.

Furthermore, the insulator is an insulating bush sleeved on the first conductor.

Furthermore, the second conductor includes a first metal sheet and a second metal sheet which are arranged opposite to each other, and the first conductor is sandwiched between the first metal sheet and the second metal sheet.

Furthermore, the first metal sheet and the second metal sheet are fixedly connected by stamping.

Furthermore, the first metal sheet is provided thereon with a first groove, the second metal sheet is provided thereon with a second groove with the second groove being opposite to the first groove, and the first conductor is clamped in the first groove and the second groove.

Furthermore, the first metal sheet includes a plurality of first metal segments provided at intervals, and first half cylinders connecting adjacent two of the first metal segments, with the first half cylinder defining the first groove; the second metal sheets includes a plurality of second metal segments provided at intervals, and second half cylinders connecting adjacent two of the second metal segments, with the second half cylinder defining the second groove.

Furthermore, the plurality of second conductors are provided thereon with first spines.

Furthermore, the plurality of second conductors are connected end to end successively via a conductive connecting piece.

Furthermore, the connecting piece is provided thereon with a second spine.

A protection monitoring system includes any one of the above metal protective nets. The protection monitoring system further includes a monitoring device, and the monitoring device is electrically connected with both the first conductors and the second conductors.

Furthermore, the protection monitoring system further includes an upper device in communication with the monitoring device.

The technical solutions of the present invention at least have the following advantages and beneficial effects:

with the metal protective net provided in the embodiments of the present invention, the first conductor and the second conductor can not only provide physical protection, but also play a role in transmitting an electrical signal as being configured to be electrically connected with the monitoring device. Once either of the first conductor or the second conductor is damaged, the monitoring device can send an alarm signal (which may trigger on-site audible and visual alarming, or may be uploaded in a wired or wireless way to an upper device for alarming). The metal protective net provided in the embodiments of the present invention can make it easy to implement integration of protection and monitoring.

BRIEF DESCRIPTION OF DRAWINGS

In order to more clearly illustrate technical solutions of embodiments of the present invention, figures which are needed in the embodiments will be introduced briefly below. It should be understood that the figures below merely show some embodiments of the present invention, and should not be considered as limiting the scope of the present invention. A person skilled in the art can obtain other relevant figures according to these figures, without paying inventive effort.

FIG. 1 is a schematic structural view of a metal protective net provided in Embodiment 1 of the present invention, as seen from the front.

FIG. 2 is a schematic structural view of a metal protective net provided in Embodiment 2 of the present invention, as seen from the front.

FIG. 3 is a schematic structural view showing one connection between a first conductor and an insulator provided in Embodiment 2 of the present invention.

FIG. 4 is a schematic structural view showing another connection between the first conductor and the insulator provided in Embodiment 2 of the present invention.

FIG. 5 is a schematic structural view showing a connection between the first conductor and a second conductor provided in Embodiment 2 of the present invention.

FIG. 6 is a schematic perspective structural view of a first metal sheet provided in Embodiment 2 of the present invention.

FIG. 7 is a schematic perspective structural view of a second metal sheet provided in Embodiment 2 of the present invention.

FIG. 8 is a partial schematic structural view of the metal protective net provided in Embodiment 2 of the present invention.

FIG. 9 is a schematic structural view of a protection monitoring system provided in Embodiment 3 of the present invention.

DETAILED DESCRIPTION OF EMBODIMENTS

In order to make the objects, technical solutions and advantages of the embodiments of the present invention clearer, below the technical solutions in the embodiments of the present invention will be described clearly and completely in conjunction with the figures in the embodiments of the present invention. Apparently, some but not all embodiments of the present invention are described. Generally, components in the embodiments of the present invention, as described and shown in the figures herein, can be arranged and designed in different configurations.

Therefore, the detailed description below of the embodiments of the present invention provided in the figures is not intended to limit the scope of protection of the present invention, but merely illustrates chosen embodiments of the present invention. Based on the embodiments of the present invention, all the other embodiments, obtained by a person ordinarily skilled in the art without paying inventive effort, should fall within the scope of protection of the present invention.

It should be noted that similar reference signs and letters represent similar items in the following figures. Therefore, once a certain item is defined in one figure, it is not needed to be further defined or explained in subsequent figures.

It should be indicated that in the description of the embodiments of the present invention, terms such as “first”

and "second" are merely for distinctive description, but should not be construed as indicating or implying relative importance.

Embodiment 1

As shown in FIG. 1, a metal protective net provided in the present embodiment includes:

a plurality of steel wires 1, where the plurality of steel wires 1 are arranged in parallel, the steel wire 1 is a steel thread or iron thread, and the cross-sectional diameter of the steel wire 1 may be configured according to practical situations; in the present embodiment, the steel wire 1 has a cross-sectional diameter of 4 mm to 5 mm;

a plurality of metal connecting sheets 2, where the plurality of metal connecting sheets 2 are arranged in parallel, and the metal connecting sheets 2 and the steel wires 1 are arranged to intersect with each other at a plurality of intersections without being connected;

insulating members 3, where the insulating members 3 are provided between the steel wires 1 and the metal connecting sheets 2 and located at the intersections, and fixedly connected with the steel wires and the metal connecting sheets;

connecting terminals 4, where both ends of each of the steel wires 1 each are connected with one of the connecting terminals 4, and both ends of each of the metal connecting sheets 2 each are connected with one of the connecting terminal 4; and

a monitoring device, where the connecting terminals 4 are electrically connected with the monitoring device.

In the present embodiment, with the provision of the insulating members and the monitoring device, the steel wires and the metal sheets, which form the metal protective net, may be insulated from each other, i.e., not electrically conductive with each other, thereby forming many individual independent loops. If the metal net is broken, an alarm may be sent by the monitoring device (which may be an on-site audible and visual alarm, or may be uploaded in a wired or wireless way to an upper device for alarming). The metal protective net provided in the present embodiment forms a multi-loop information transmitting channel, and enables the integration of protection and monitoring.

As shown in FIG. 1, the metal connecting sheet 2 includes: a first metal sheet, where the first metal sheet is arranged on one side of the plurality of steel wires 1, forming a plurality of intersections; a second metal sheet, where the second metal sheet is arranged on the other side of the plurality of steel wires 1 and located at the plurality of intersections. The steel wire 1 is fixed, at each of the intersections, with one of the insulating members 3 by bonding or riveting. Both the first metal sheet and the second metal sheet are fixedly connected with the insulating member 3. In the present embodiment, both the first metal sheet and the second metal sheet are connected with the insulating member 3 by mold stamping. By providing the first metal sheets and the second metal sheets at both sides of the steel wires, respectively, tight intersections are formed in the metal net as the metal connecting sheets hold the insulating members tightly.

As shown in FIG. 1, in the present embodiment, the insulating member 3 is of a cylindrical shape, and the insulating member 3 is sleeved outside the steel wire 1 and fixedly connected therewith. The first metal sheet and the second metal sheet are arranged opposite to each other, and both of them are bonded or riveted onto an outer wall of the insulating member 3. By setting the insulating member to be

in a cylindrical shape and sleeved outside the steel wire, the steel wire can be effectively isolated from the metal sheet.

As shown in FIG. 1, in the present embodiment, the first metal sheet and the second metal sheet are provided thereon with burrs 21, with the burrs 21 located between two adjacent steel wires 1. By providing burrs on the metal sheets, it is possible to prevent people or animals from climbing into a protection zone by force, which can thus further enhance the protective effect in the aspect of hardware.

As shown in FIG. 1, in the present embodiment, every two adjacent steel wires 1 are connected end to end successively via a conducting wire, so as to form a first conductor, and every two adjacent metal connecting sheets 2 are connected 15 end to end successively via a conducting wire, so as to form a second conductor. One end of the first conductor and one end of the second conductor are both connected, via a conducting wire, with one connecting terminal 4, and the other end of the first conductor and the other end of the 20 second conductor are both connected, via a conducting wire, with one connecting terminal 4. In the metal protective net provided in the present embodiment, steel threads are adopted for longitudinal steel wires, and two layers of metal sheets are adopted in the horizontal direction, with the steel threads sandwiched between the two layers of metal sheets. The metal sheets and the steel threads are connected together by stamping with a large mold. Moreover, according to 25 standard of electrical apparatus, the metal sheets and the steel threads form two independent conductive channels, which are insulated from each other, in the vertical direction and in the horizontal direction, respectively. If the metal net is broken, an alarm may be sent by the monitoring device (which may be an on-site audible and visual alarm, or may be uploaded in a wired or wireless way to an upper device for alarming). This enables a multi-loop information transmitting channel, and thus the integration of protection and monitoring.

Embodiment 2

As shown in FIG. 2, the present embodiment provides a metal protective net 10. The metal protective net 10 includes a plurality of first conductors 110, a plurality of second conductors 120 and insulators (as shown in FIG. 3 and FIG. 4).

The plurality of first conductors 110 are arranged side by side, and connected end to end successively, forming a continuous conductive path. The plurality of second conductors 120 are arranged side by side, and connected end to end successively, forming a continuous conductive path. The first conductors 110 and the second conductors 120 are arranged to intersect with each other, and the first conductors 110 and the second conductors 120 are connected at intersections therebetween to form a net. The insulators are 55 provided at the intersections between the first conductors 110 and the second conductors 120, and the insulators are configured to make the first conductors 110 and the second conductors 120 non-conductive with each other.

In this way, the first conductors 110 and the second conductors 120 form two independent conductive paths, respectively. The first conductors 110 and the second conductors 120 are configured to be electrically connected with a monitoring device (not shown in the figures), and play a role in transmitting electrical signals. When either of the first conductors 110 or the second conductors 120 is damaged, the electrical signal transmission is interrupted, at that time, the monitoring device may send an audible and visual alarm

signal, or transmit such information to an upper device. The first conductors **110** and the second conductors **120** intersect with each other and thus form a net, thereby providing physical protection; and meanwhile, the first conductors **110** and the second conductors **120** also play a role in transmitting electrical signals, such that the metal protective net **10** provided in the present embodiment can make it easy to implement the integration of protection and monitoring.

Below the metal protective net **10** provided in the present embodiment will be further described.

Referring to FIG. 2 again, in the present embodiment, one metal conducting wire is bent at several points so as to be in a zigzag shape, which includes a plurality of rectilinear extending portions side by side, and bent portions connecting adjacent rectilinear extending portions. In this case, the rectilinear extending portions form the first conductors **110**. It can be understood that the plurality of first conductors **110** also can be obtained in other ways, other than being obtained by bending an integral metal conducting wire. For example, the plurality of first conductors **110** may be independent from each other, and adjacent first conductors **110** are connected via a conductive metal connecting line, thus forming a continuous conductive path.

Referring to FIG. 3, the metal conducting wire is wrapped by an insulating layer **111**, and the insulating layer **111** wraps an outer peripheral surface of the metal conducting wire along an extending direction of the metal conducting wire, so that the metal conducting wire is insulated from the outside. A part of the insulating layer **111**, which is located at the intersection between the first conductor **110** and the second conductor **120**, forms the insulator. In other embodiments, referring to FIG. 4, the insulators may also be a plurality of insulating bushes **130** sleeved on the first conductor **110**. Adjacent insulating bushes **130** are spaced apart from each other, so that the first conductor **110** is only insulated at intersections from the second conductors **120**, whereas the other portions of the first conductors **110** are exposed.

In the above, the insulators may be made from a material such as TPU (Thermoplastic polyurethane), PVC (Polyvinyl chloride) or ABS (Acrylonitrile butadiene Styrene copolymer).

There may be various ways of connecting the first conductor **110** and the second conductor **120** at the intersections. For example, the first conductor **110** and the second conductor **120** may be bound together by a rope, or the first conductor **110** and the second conductor **120** may be braided together. In the present embodiment, referring to FIG. 5, the connection between the first conductor **110** and the second conductor **120** is realized in a way as follows. The second conductor **120** includes a first metal sheet **121** and a second metal sheet **122** which are arranged opposite to each other. The first metal sheet **121** and the second metal sheet **122** fit together with each other, and the first conductor **110** is sandwiched between the first metal sheet **121** and the second metal sheet **122**, thereby realizing the connection between the first conductor **110** and the second conductor **120**.

Further, referring to FIG. 6 and FIG. 7, the first metal sheet **121** is provided thereon with first grooves **1211**, and the second metal sheet **122** is provided thereon with second grooves **1221**. The first grooves **1211** correspond one to one to the second grooves **1221**. Once the first metal sheet **121** and the second metal sheet **122** fit together with each other, the first groove **1211** and the second groove **1221** face each other and form a receiving space. The first conductor **110** is clamped in the receiving space formed by the first groove

1211 and the second groove **1221**. In this way, the first conductor **110** and the second conductor **120** may be more stably connected.

Further, referring to FIG. 6 and FIG. 7, in the present embodiment, the first groove **1211** and the second groove **1221** are realized in a way as follows. The first metal sheet **121** includes a plurality of first metal segments **1212** provided at intervals, and first half cylinder **1213** connecting adjacent first metal segments **1212**, with the first half cylinder **1213** defining the first groove **1211**. The second metal sheet **122** includes a plurality of second metal segments **1222** provided at intervals, and second half cylinders **1223** connecting adjacent second metal segments **1222**, with the second half cylinder **1223** defining the second groove **1221**. Once the first metal sheet **121** and the second metal sheet **122** fit together with each other, the first half cylinder **1213** and the second half cylinder **1223** face each other, and are jointly sleeved on the first conductor **110**, thereby realizing the connection between the first conductor **110** and the second conductor **120**. Both the first metal segment **1212** and the second metal segment **1222** are provided thereon with first spines **124**, so as to improve the physical protective effect of the metal protective net **10**.

The first metal sheet **121** and the second metal sheet **122** may be fixedly connected with each other in a variety ways, for example, welding, bolted connection or riveting. In the present embodiment, the first metal sheet **121** and the second metal sheet **122** are fixedly connected in a way as follows. Referring to FIG. 5 and FIG. 6, the first metal segment **1212** is provided thereon with a protruding crimping plate **1214**. The crimping plate **1214** may be bent by stamping so that the second metal segment **1222** is pressed against the first metal segment **1212**, thus realizing the fixed connection between the first metal sheet **121** and the second metal sheet **122**.

Referring to FIG. 8, in the present embodiment, the plurality of second conductors **120** are connected end to end successively via conductive connecting pieces **123**. The connecting piece **123** is provided thereon with a second spine (not shown in the figure), so as to improve the physical protective effect of the metal protective net **10**.

Embodiment 3

Referring to FIG. 9, the present embodiment provides a protection monitoring system **20**. The protection monitoring system **20** includes the metal protective net **10** described in Embodiment 2. The protection monitoring system **20** further includes a monitoring device. In the present embodiment, the monitoring device includes a first monitoring device **210** and a second monitoring device **220**. Both ends of the continuous conductive path formed by the first conductors **110** are connected with the first monitoring device **210** and the second monitoring device **220**, respectively. Both ends of the continuous conductive path formed by the second conductors **120** are connected with the first monitoring device **210** and the second monitoring device **220**, respectively. The first conductors **110** and the second conductors **120** transmit electrical signals between the first monitoring device **210** and the second monitoring device **220**. When either of the first conductors **110** or the second conductors **120** is damaged, the electrical signal transmission is interrupted, at that time, the first monitoring device **210** and the second monitoring device **220** would send an alarm signal.

Optionally, in the present embodiment, the protection monitoring system **20** further includes an upper device **230**. The upper device **230** is in communication with the first monitoring device **210** and the second monitoring device

220 in a wired or wireless manner. When either of the first conductor 110 or the second conductor 120 is damaged, the first monitoring device 210 and the second monitoring device 220 would send an alarm signal to the upper device 230, thus realizing a remote alarm function. Exemplarily, the upper device 230 may be a computer.

The foregoing only describes partial embodiments of the present invention and is not intended to limit the present invention. For a person skilled in the art, various modifications and variations may be made to the present invention. Any modifications, equivalent replacements, improvements, etc., made within the spirit and principle of the present invention, should be covered by the scope of protection of the present invention.

The invention claimed is:

1. A metal protective net, comprising:

a plurality of steel wires (1), wherein the plurality of steel wires (1) are arranged in parallel;

a plurality of metal connecting sheets (2), wherein the plurality of metal connecting sheets (2) are connected end to end successively and arranged in parallel, and the metal connecting sheets (2) and the steel wires (1) are arranged to intersect with each other at a plurality of intersections without being connected;

insulating members (3), wherein the insulating members (3) are provided between the steel wires (1) and the metal connecting sheets (2) and located at the intersections, and fixedly connected with the steel wires (1) and the metal connecting sheets (2);

connecting terminals (4), wherein both ends of each of the steel wires (1) each are connected with one connecting terminal (4), and both ends of each of the metal connecting sheets (2) are connected with two different connecting terminals (4); and

a monitoring device, wherein the connecting terminals (4) are electrically connected with the monitoring device.

2. The metal protective net according to claim 1, wherein the metal connecting sheet (2) comprises:

a first metal sheet, wherein the first metal sheet is arranged on one side of the plurality of steel wires (1), forming a plurality of intersections;

a second metal sheet, wherein the second metal sheet is arranged on the other side of the plurality of steel wires (1) and located at the plurality of intersections;

the steel wire (1) is fixed, at each of the plurality of intersections, with one of the insulating members (3) by bonding or riveting, and the first metal sheet and the second metal sheet are respectively located at both sides of the steel wire and fixedly connected onto an outer side wall of the insulating member (3).

3. The metal protective net according to claim 2, wherein both the first metal sheet and the second metal sheet are fixedly connected with the insulating member (3) by mold stamping.

4. The metal protective net according to claim 3, wherein the insulating member (3) is of a cylindrical shape, and the insulating member (3) is sleeved outside the steel wire (1), and fixed with the steel wire by bonding or riveting.

5. The metal protective net according to claim 4, wherein the first metal sheet and the second metal sheet are provided thereon with burrs (21), with the burrs 21 located between adjacent two of the steel wires (1).

6. The metal protective net according to claim 5, wherein every adjacent two of the steel wires (1) are connected end to end successively via a conducting wire, so as to form a first conductor, every adjacent two of the metal connecting sheets (2) are connected end to end successively via a

conducting wire, so as to form a second conductor, one end of the first conductor and one end of the second conductor are both connected, via a conducting wire, with one connecting terminal (4), and the other end of the first conductor and the other end of the second conductor are both connected, via a conducting wire, with one connecting terminal (4).

7. The metal protective net according to claim 1, wherein the steel wire (1) is a steel thread or iron thread having a cross-sectional diameter of 4 mm to 5 mm.

8. A metal protective net, comprising:

a plurality of first conductors, wherein the plurality of first conductors are arranged side by side, and connected end to end successively, forming a continuous conductive path;

a plurality of second conductors, wherein the plurality of second conductors are arranged side by side, and connected end to end successively, forming a continuous conductive path; and

insulators,

wherein the first conductors and the second conductors are arranged to intersect with each other, and the first conductors and the second conductors are connected at intersections to form a net; the insulators are provided at the intersections between the first conductors and the second conductors, and the insulators are configured to make the first conductors and the second conductors non-conductive with each other.

9. The metal protective net according to claim 8, wherein the plurality of first conductors are formed by bending one metal conducting wire at several points.

10. The metal protective net according to claim 9, wherein the metal conducting wire is wrapped by an insulating layer, and a part of the insulating layer, which is located at the intersection between the first conductor and the second conductor, forms the insulator.

11. The metal protective net according to claim 8, wherein the insulator is an insulating bush sleeved on the first conductor.

12. The metal protective net according to claim 8, wherein the second conductor comprises a first metal sheet and a second metal sheet which are arranged opposite to each other, and the first conductor is sandwiched between the first metal sheet and the second metal sheet.

13. The metal protective net according to claim 12, wherein the first metal sheet and the second metal sheet are fixedly connected by stamping.

14. The metal protective net according to claim 12, wherein the first metal sheet is provided thereon with a first groove, the second metal sheet is provided thereon with a second groove with the second groove being opposite to the first groove, and the first conductor is clamped in the first groove and the second groove.

15. The metal protective net according to claim 14, wherein the first metal sheet comprises a plurality of first metal segments provided at intervals, and first half cylinders connecting adjacent two of the first metal segments, with the first half cylinder defining the first groove; the second metal sheet comprises a plurality of second metal segments provided at intervals, and second half cylinders connecting adjacent two of the second metal segments, with the second half cylinder defining the second groove.

16. The metal protective net according to claim 8, wherein the plurality of second conductors are provided thereon with first spines.

17. The metal protective net according to claim **8**, wherein the plurality of second conductors are connected end to end successively via a conductive connecting piece.

18. The metal protective net according to claim **17**, wherein the connecting piece is provided thereon with a ⁵ second spine.

19. A protection monitoring system, comprising the metal protective net according to claim **8**, wherein the protection monitoring system further comprises a monitoring device, and the monitoring device is electrically connected with ¹⁰ both the first conductors and the second conductors.

20. The protection monitoring system according to claim **19**, wherein the protection monitoring system further comprises an upper device in communication with the monitoring device. ¹⁵
